UNITED STATES PATENT OFFICE.

CEPHAS MANNING, OF BOSTON, MASSACHUSETTS.

FEED-WATER HEATER.

SPECIFICATION forming part of Letters Patent No. 337,510, dated March 9, 1886.

Application filed June 18, 1885. Serial No. 169,023. (No model.)

To all whom it may concern:

Be it known that I, CEPHAS MANNING, of Boston, in the county of Suffolk, in the State of Massachusetts, a citizen of the United States, 5 have invented a certain new and useful Improvement in Feed-Water Heaters for Locomotive and other Boilers, of which the following is a full, clear, and exact description, reference being had to the accompanying drawings, 10 forming a part of this specification, in explaining its nature.

The object of the invention is to provide a cheap and efficient device for heating the feed-water which is supplied locomotive and 15 other boilers, and it comprises the arrangement in the smoke-box of the boiler of a pipe of any desired size or form, arranged to extend about the flue-sheet of the boiler in close proximity thereto, and adapted to be passed 20 over or under the dry-pipe, as may be desired. This arrangement of the pipe in the smoke-box is such that it does not interfere with the ready access to the boiler-flues for the purpose of cleaning or repairs, while at the same 25 time it is so arranged as to receive the heat passing from the boiler-flues.

In the drawings, Figure 1 is a side view of a smoke-box containing my improved heater, and Fig. 2 is an end view of the same. 30 A represents a portion of the locomotive-boiler; a, the flues; B, the smoke-box; C, the sheet which forms the smoke-box and exterior of the boiler; D, the dry-pipe; E, the exhaust; F, the feed-water-heating device or chamber. 35 Its casing is represented as round or in the form of a pipe; but it may be oval, rectangular, square, or of any other desired section, so long as it has the arrangement in the smoke-box in relation to the outer plate of the smoke-box 40 or boiler herein shown and described. Its end G is connected with a pipe, g, extending from the injector or pump or other water-forcing device, (not shown,) and its other end, G', connects with a pipe, g', entering the boiler.

45 In the drawings the device is shown as applied to a boiler, and I have represented the water-chamber as formed by two coils of a pipe extending about it close to the flue-plate.

In lieu of arranging the coils as represent- 50 ed—that is, as passing under the dry-pipe—they may pass over the same.

In operation the feed-water is forced,

pumped, or injected into the pipe or heating-chamber within the smoke-box, and is thus caused to be circulated or moved through the 55 smoke-box into the boiler, and is of course thereby exposed to the heat which passes from the flues to the smoke-box.

In stationary boilers the arrangement of the heating chamber or pipe in relation to the 60 boiler shell and flues is substantially the same.

It will be observed that this construction is very simple, very cheap, and does not in any way obstruct the smoke-box or prevent easy 65 access to the boiler.

When a pipe is used to form the heater-chamber, it may be of the size of the ordinary feed-pipe, and it may be extended around the smoke-box once, twice, or as many times as may be desirable; but I wish it to be understood that I do not confine myself to the especial size, shape, or construction of this pipe or chamber within the smoke-box, so long as it is arranged in the smoke-box in relation to the smoke-box or boiler-sheet and flues substantially as herein shown and described. I prefer, also, to arrange the joints or connections of the heating chamber or pipe with the pipes connecting the water-forcing device therewith, and connecting it with the boiler so that they 75 shall come outside of the smoke-box, to prevent their exposure to the heat of the smoke-box, and in order that they may be easily reached for repairs, &c.

I would state that the heater may be arranged 85 at either end of a cylinder or other shaped boiler, so long as it shall bear the relation to the flues of the boiler and the casing of the chamber or box holding it herein specified.

Having thus fully described my invention, 90 I claim and desire to secure by Letters Patent of the United States—

1. A feed-water heater for locomotive and other boilers, comprising a continuous or unbroken pipe arranged in the smoke-box of the 95 boiler in close proximity to the casing there-of, to extend about the smoke-box, and also in close proximity to the flue-sheet of the boiler, one end of which pipe is connected outside the smoke-box with the boiler, as specified, and 100 the other of which is connected outside the boiler with a source of water-supply, all substantially as and for the purposes set forth.

2. The combination, in a feed-water heater

for locomotive and other boilers, of the smoke-box, the flue-sheet of the boiler, and a feed-water heater consisting of a coil of pipe extending about the inner surface of the smoke-box and in close proximity to the flue-sheet

5 of the boiler, connected at one end with an injector or pump, and at the other end with a

boiler, all substantially as and for the purposes specified.

CEPHAS MANNING.
